UNITED STATES PATENT OFFICE.

LUTHER O. MARTIN, OF PARKERSBURG, WEST VIRGINIA.

INTERNAL-COMBUSTION ENGINE.

1,073,770.

Specification of Letters Patent. Patented Sept. 23, 1913.

Application filed January 25, 1912. Serial No. 673,458.

To all whom it may concern:

Be it known that I, LUTHER O. MARTIN, a citizen of the United States, residing at Parkersburg, in the county of Wood and State of West Virginia, have invented certain new and useful Improvements in Internal-Combustion Engines, of which the following is a specification.

My invention relates to internal combustion engines of the type that include a plurality of explosion cylinders and employ a single rotatable valve to control the inlet and exhaust of gases to and from the cylinders, and has particular reference to an engine of this character provided with a novel lubricating system, adapted to not only lubricate the valve but the driving means therefor.

An important object of this invention is to provide a lubricating system of the above mentioned character, which is simple in construction and continuous and reliable in operation.

In the accompanying drawings forming a part of this specification and in which like numerals are employed to designate like parts throughout the same, Figure 1 is a front side view of the engine, and, Fig. 2 is a central vertical longitudinal sectional view through the same.

In the drawings, wherein is illustrated a preferred embodiment of my invention, the numerals 1, 2, 3, and 4 designate explosion cylinders, which are preferably vertically disposed. These explosion cylinders are connected with the usual crank-case, (not shown). Disposed to reciprocate within each explosion cylinder is a piston 6, connected with a pitman 7, as shown. The explosion cylinders are surrounded by a jacket 8, providing a water space 9, as shown.

The numeral 12 designates spark plugs.

The numeral 18 designates a valve housing, which is suitably mounted upon the explosion cylinders and is preferably provided with a water space 19, having free communication with the water space 9, as shown. The valve housing 18 is provided with a tapered or frusto-conical opening 20, for receiving a rotatable tapered valve 28, provided with transverse openings 29, adapted to be moved into and out of registration with inlet and exhaust ports (not shown) which lead into the explosion cylinders. The valve 28 is held against longitudinal movement in one direction by a set screw 32, engaging a

head 33', which is rigidly connected with the valve housing 18. At its opposite end the valve 18 is provided with a reduced extension 37, upon which is rigidly mounted a beveled gear 41, engaged by a beveled gear 42, which is rigidly mounted upon the upper end of a vertical actuating shaft 43. The beveled gears 41 and 42 are disposed within a housing or shell 41^a, rigidly connected with the valve casing 18, as shown. 65

The numeral 42^a designates a set screw operating through a screw-threaded opening in the housing or shell 41^a and engaging the reduced extension 37 of the valve 28. The function of this set screw is to positively 70 limit the longitudinal movement of the valve 28 in one direction.

The numeral 44 designates an oil force pump, which is geared to the actuating shaft 43 through the medium of bevel-gears 45 75 and 46. This pump draws oil from an oil supply tank 47, through the medium of a connecting pipe 48 and discharges the oil through a pipe 49. The head 18 is provided through its upper portion with a series of 80 properly spaced U-shaped openings 50. These U-shaped openings have their upper ends extending through the outer surface of the head 18 and their inner horizontal connecting portions leading into the opening 20, 85 as shown. The pipe 49 leads into the first U-shaped opening 50 to the right, as shown at 51. These U-shaped openings are connected by inverted approximately U-shaped conduits 52. Leading into the first U- 90 shaped opening 50 to the left, as shown at 53, is a return pipe 54, which passes into the shell 41^a, as shown at 55. It is thus seen that the U-shaped openings 50 and the pipes 52 form in effect, a perforated conduit for 95 supplying oil to the valve 28. A pipe 56 connects the tank 47 and shell 41^a.

The operation of the engine is as follows:—When the engine is operating, the pump 44 will draw the oil or lubricant from the tank 47 through pipe 48 and force the same through pipe 49 into the pipes 52 and ports 50, which form in effect a perforated conduit, to supply the oil to the valve 28. The oil is then forced through the return pipe 54 and discharges upon the beveled gears 41 and 42 within the shell or housing 41^a, which collects the same so that the oil may be returned to the tank 47 through the pipe 56. It is thus seen that the circulation 105 110

of the oil or other lubricant is continuous and the same not only lubricates the valve but the driving means therefor. This lubricant is effected without any unnecessary 5 waste of the lubricant.

It is to be understood that the form of my invention herewith shown and described, is to be taken as a preferred example of the same and that certain changes in the shape, 10 size, and arrangement of parts may be resorted to without departing from the spirit of the invention or the scope of the subjoined claims.

Having thus described my invention, I 15 claim:—

1. In an engine of the character described, a plurality of cylinders, a head connected therewith and provided with an axial opening having means of communication with 20 the interior of the cylinders, a rotary valve disposed within the axial opening, a shell connected with the head, driving means for said rotary valve including gears disposed within the shell, a perforated conduit for 25 supplying oil to the rotary valve, and a return conduit connected with the perforated

conduit and discharging the oil back into said shell to lubricate the elements therein.

2. In an engine of the character described, a plurality of cylinders, pistons operating therein, a head connected with the cylinders and provided with an axial opening having means of communication with the interior of the cylinders, a rotary valve disposed within the axial opening, a shell connected with the head, driving means for said rotary valve including gears disposed within the shell, a supply tank having means of communication with said shell, a pump having means of communication with the supply tank, a perforated conduit to supply the oil to the rotary valve and having means of communication with the pump, a return pipe connected with the perforated conduit and discharging into the shell to lubricate the elements therein, and means to operate the pump. 40

In testimony whereof I affix my signature in presence of two witnesses.

LUTHER O. MARTIN.
